UNITED STATES PATENT OFFICE.

SAMUEL M. CHARLES, OF TOPEKA, KANSAS.

SLEEPING-CAR.

SPECIFICATION forming part of Letters Patent No. 485,151, dated October 25, 1892.

Application filed May 31, 1892. Serial No. 434,850. (No model.)

To all whom it may concern:

Be it known that I, SAMUEL M. CHARLES, a citizen of the United States, residing at Topeka, in the county of Shawnee and State of 5 Kansas, have invented certain new and useful Improvements in Sleeping-Cars; and I do hereby declare the following to be a full, clear, and exact description of the invention, such as will enable others skilled in the art to which 10 it appertains to make and use the same.

This invention relates to a new and useful improvement in sleeping-cars; and it consists in the construction and arrangements of the parts hereinafter described, and definitely 15 pointed out in the claims.

The invention further consists in an improvement on the construction illustrated and described in Letters Patent No. 468,493, granted to myself on the 9th day of February, 1892.

20 The aim and purpose of my present invention is to add security to the support of the bracket, to so arrange the platform and step that a simultaneous movement may be had to swing or move the same into a vertical position, and to increase the rigidity of the 25 structure. This object is obtained by the construction illustrated by the accompanying drawings, in which like letters of reference indicate corresponding parts in the several 30 views, and in which—

Figure 1 is a perspective view of the improvement. Fig. 2 is a perspective view of the bracket, looking toward the rear; and Fig. 3 is a front elevation with the steps elevated.

35 In the drawings, A represents the end of the car-seat, B metallic eyes fitted in the end of the seats, and C a slotted plate in the floor.

The bracket D is substantially the same as shown in the patent above mentioned, with 40 the exception of having the tongue d on its lower end, which fits in the slotted plate on the floor.

The securing-hooks E are formed with heads e, which fit in the eyes on the end of the seat, 45 and are there locked in position.

The platform F is made of a single piece and is hinged to the upper arm of the bracket at or near the inner edge of the platform. Its rear end is reduced and formed into a right-angle extension f. The step or lower platform is constructed in a manner similar to

the upper platform and has an extension g. These extensions are arranged adjacent to the inner face of the bracket near the rear edge thereof, and are connected with a connecting-bar H, so that as soon as either the step or platform is moved the other will be simultaneously moved. By hinging the step and platform at their edges it will be seen that when down they will project out into the aisle, and when not in use by moving the same up into a vertical plane they are thrown back to a position near the seat.

To give additional strength and rigidity to the structure, suitable bracing-blocks I are 65 secured to the under face of the platform and step, which engages the side of the bracket-arm and prevents the platform or step from assuming a position other than a horizontal when the same are adjusted for use. The extensions on the ends of the platform and step engage the inner face of the bracket when the platform and step are adjusted for use, thereby assisting in holding the same in a horizontal position.

75 By the above-described construction it will be seen that the bracket is firmly supported and held in place and at the same time may be quickly removed. By having both the step and platform hinged the advantage, in 80 addition to the one above mentioned, is that the attachment may be more easily stored away with the bedding in the upper berth or other convenient place.

I am aware that many minor changes can 85 be made in the construction and arrangements of parts and substituted for those herein shown and described without in the least departing from the nature and principle of my invention.

Having thus described my invention, what 90 I claim as new, and desire to secure by Letters Patent, is—

1. In a sleeping-car, the combination, with a fixed support, of a bracket removably supported thereby, having a series of steps arranged on different horizontal and vertical planes, hinged directly thereto and extending out therefrom, substantially as described.

2. In a sleeping-car, the combination, with 100 the seat and floor eyes in the seats, and a slotted plate in the floor, of a bracket having

attaching means engaging the eyes and a tongue engaging the slot in the plate on the floor and hinged steps on the bracket, substantially as described.

5. 3. In a bracket, the combination, with the arms thereof, and means for securing the bracket in position, of steps hinged at their inner edges to the arms and having their outer edges projecting laterally beyond the

10 arms, substantially as described.

4. In a platform-bracket for sleeping-cars, the combination, with the arms of the bracket, of steps hinged to the arms and a connection

between the steps independent of the bracket, substantially as described.

5. In a platform-bracket, the combination, with the arms of the bracket, of steps hinged to the arms, having extensions arranged to engage the bracket when the steps are in a horizontal position, substantially as described.

In testimony whereof I affix my signature in presence of two witnesses.

SAMUEL M. CHARLES.
